UNITED STATES PATENT OFFICE.

OLIVIA P. FLYNT, OF BOSTON, MASSACHUSETTS.

IMPROVEMENT IN Undershirts.

Specification forming part of Letters Patent No. 146,175, dated January 6, 1874; application filed November 13, 1873.

To all whom it may concern:

Be it known that I, OLIVIA P. FLYNT, of Boston, in the county of Suffolk and State of Massachusetts, have invented a new and valuable Improvement in Children's Undershirts and Supporters, of which the following is a full, clear, and exact description, reference being had to the accompanying drawing forming a part of this specification.

In this invention a child's undershirt is so constructed as to support, from the tips of the shoulders, the drawers and stockings, with the utmost ease and comfort to the wearer. It is intended for either sex, and may be made with long or short sleeves.

In the accompanying illustration, Figure 1 is a front view of the shirt, drawers, and stockings, in the position assumed when in use. Fig. 2 is a front view of the drawers and stockings detached from the shirt. Fig. 3 is a rear view of the shirt. Fig. 4 is a rear view of the drawers and stockings. Fig. 5 is a view of one of the stocking-supporters.

Similar letters of reference indicate corresponding parts.

a is an undershirt for boys or girls, to be worn next the skin, and opening behind the full length of the shirt, from *x* to *y*. *a'* are the buttons, used only for the purpose of closing and fastening the shirt behind. *b* is the drawers, open entirely behind and partially in front, buttoned over behind by the button *g*. *c e* are the stockings. *d e* are bands, non-elastic, sewed to the shirt, and passing over the tips of the shoulders. They are made a trifle longer than necessary, so that certain buttons, below described, may be moved lower, as the growth of the child requires it. *f* is a band passing down the front of the shirt, similar to the bands *d e*. *g g'* are buttons upon the drawers *b*, which button into button-holes *g''* in the bands *d e f* in front and behind, and at the opening behind. The position of the drawers inside the shirt is shown by the broken line *b'*, Fig. 1.

Thus it will be seen that the drawers are

supported entirely by the bands *d e f*, sewed upon the shirt *a*, instead of being supported by the waist.

It is not necessary to separate the shirt *a* and drawers *b* when dressing and undressing, as the shirt *a* is open at the full length behind. Again, inasmuch as the drawers are made open, somewhat after the style of some ladies' drawers, it is not necessary to unbutton the drawers from the shirt to attend to the calls of nature.

m m are stocking supporters. It will be noticed that they are crossed and stitched at the center. This makes them firmer and more compact. They button onto the buttons *k* in the stockings, and *h* in the shirt. The buttons *h* are placed in the bands *d e* below the buttons *g*, so that the stocking is also supported from the shoulder.

It will be seen, from this description, that both drawers and stockings are supported by the tips of the shoulders, while all three of the garments shown are easy for the child to wear. The shirt and drawers, inasmuch as they do not require separating, are easily taken off and put on. In case no overwaist is worn, the skirts and cotton drawers may be suspended from the buttons *g g'*.

Having thus fully described my invention, what I claim as new, and desire to secure by Letters Patent, is—

1. The combination and arrangement, with the shirt *a*, open the full length behind, of the bands *d e f*, said bands being provided with button-holes *g''* to receive the buttons *g* of the drawers, and buttons *h* to hold the stocking-supporters *m*, substantially as and for the purposes herein described.

2. The stocking-supporter *m*, of the form illustrated, in combination with the buttons *k* and *h*, as and for the purpose above specified.

OLIVIA P. FLYNT.
